(57) **CLAIM**

The ornamental design for an inflatable dog bed, as shown and described.

DESCRIPTION

FIG. 1 is a perspective view of the inflatable dog bed showing my new design;

FIG. 2 is a top plan view thereof;

FIG. 3 is a left side elevational view thereof;

FIG. 4 is a right side elevational view thereof;

FIG. 5 is a bottom plan view thereof;

FIG. 6 is a front elevational view thereof; and,

FIG. 7 is a rear elevational view thereof.

The dashed lines in FIGS. 1, 3, 4 and 7 represent conventional stitching.
